CLAIM

The ornamental design for a desktop ambient light, as shown and described.

DESCRIPTION

FIG. 1 is a front and top perspective view of a desktop ambient light showing my new design.

FIG. 2 is a rear and bottom perspective view of a desktop ambient light.

FIG. 3 is a front view of a desktop ambient light.

FIG. 4 is a rear view of a desktop ambient light.

FIG. 5 is a left side view of a desktop ambient light.

FIG. 6 is a right side view of a desktop ambient light.

FIG. 7 is a top view of a desktop ambient light.

FIG. 8 is a bottom view of a desktop ambient light; and,

FIG. 9 is a perspective view of the desktop ambient light in an alternate configuration of use, in which the base is installed in the middle portion of the desktop ambient light. Any shading or hatching is not a feature of the design but is utilized to illustrate the surface contours of the desktop ambient light in the drawings.
